OIL BURNER

Lewis L. Scott, St. Louis, Mo.

Application February 29, 1940, Serial No. 321,508

4 Claims. (CL 158—36.3)

This invention relates to oil burners of the general type known as "pressure" oil burners, whereby the oil is pumped under 100# or more pressure to a spray nozzle, and atomization takes place by virtue of the pressure on the oil through a nozzle arranged for atomizing the oil and projecting it in the form of an oil spray from the nozzle.

One of the objects of this invention is to provide a pressure type of oil burner that will burn 10 what is commonly known as #3 fuel oil or lighter fuel oils reliably down to one half gallon per hour, and still at the same time provide a nozzle orifice and nozzle whirling slots of such area even when burning at one half gallon per hour, that 15 said nozzle orifice and slots will be substantially non-clogging.

Another object is to provide a burner that will be fully automatic and that will function without manual attention.

Another object is to provide an oil burner whereby the oil rate can be adjusted to a small fraction of a gallon without the necessity of changing the spray nozzle as is commonly done in automatic pressure oil burners.

Another object is to construct the nozzle orifice of my oil burner so that there will be no dripping of oil from the nozzle during the spraying operation.

Various other objects and advantages will be apparent from the following description, and the novel features will be pointed out in the appended claims.

It is a well known fact that when attempting to burn #3 fuel oil in the conventional pressure burner that it is quite difficult to successfully operate a pressure burner down to a gallonage as low as one gallon per hour, because of the difficulty of constructing a nozzle that will give the proper spray and proper combustion, and 40 because of the smallness of the nozzle orifice, which will easily clog with any fine foreign matter that might be in the oil. For this reason, most pressure oil burners only operate down to about one and one third gallons per hour, and 45 with the nozzles used at this gallonage, considerable nozzle blocking occurs due to the very small nozzle orifice, even though great care is exercised in filtering or screening the oil.

It is highly desirable to burn oil in small quantities for oil burning water heaters, and for heating plants used in small homes. For example, many small homes have a heat loss of between 40,000 and 50,000 B. t. u.'s. The average #3 oil contains approximately 140,000 B. t. u.'s 50

per gallon, and from the above it will be seen that it would be highly desirable to be able to burn small quantities of oil efficiently and without nozzle blocking. It is also desirable in an 5 automatic burner to be able to adjust the oil fire nicely without having to take out the nozzle and change to another size.

The accompanying drawings illustrate my invention.

Referring now to the drawings,

Figure 1 is a plan view of my oil burner shown partly in section.

Figure 2 is an enlarged view of the spray nozzle and connected parts, on line 2—2 of Figure 1.

Figure 3 is an enlarged view of the oil pipes and connections leading to and from the spray nozzle.

Figure 4 is a sectional view of an automatic cut-off and pressure regulating valve connected in the return oil line from the nozzle taken on 20 the line 4—4 of Figure 1.

Figure 5 is a cross section of the oil pump, taken on the line 5—5 of Figure 6.

Figure 6 is a cross section of the pump taken on the line 6—6 of Figure 5.

Figure 7 is a front view of the nozzle whirler tip taken on the line 7—7 of Figure 2.

Referring now to the drawings, 1 indicates an electric motor which operates a blower wheel (not shown) in the blower housing 2, which blower furnishes air to the oil spray to promote combustion. 3 indicates a pump support secured to the blower housing 2, and which carries the oil pump 4. 5 indicates an air blast tube which carries the nozzle, nozzle pipe, etc. and which is adapted to direct the air from the blower 2 around the spray nozzle 6.

The pump 4 is connected to an oil supply tank, not shown, by the pipe 7. The motor 1 is adapted to drive the pump shaft 8 in a well known manner. 9 indicates a conventional type of pump packing or seal. 10 indicates a well known type of pump gears, which gears are driven by the shaft 8, and are enclosed in the housing 11, which housing is provided with an end plate cover 12, all of which parts are enclosed in the main pump casting 4, which pump casting 4 is provided with a cover plate 13. 14 indicates an oil screen for filtering the oil going into the pump. Oil is delivered from the discharge side of the pump gears to an oil passage, not shown, which passage communicates with the chamber 15 (see Figure 6). From the chamber 15 oil will be delivered through the pipe 16 and through connection 17 to the inside of the member 18, through pipe 19, through the oil screen 20, through slots

21 in the member 21A, through the chamber 22, through the nozzle whirler slots 23 in the member 23A, into the whirling chamber 24. Part of the oil will be delivered through the nozzle orifice 25 in the nozzle 6, and a part of the oil will be returned to the pump or to the tank through the hole 26 in the member 23A, through hole 27 in the member 28, through hole 29 in tube 30, through the fitting 31, through pipe 32, through the valve body 33, through pipe 34, into the suction side of the pump 4. It is obvious that this by-passed oil could be returned to the oil tank instead of into the suction side of the pump 4.

As before mentioned, oil is delivered from the pump to the chamber 15. 35 indicates a bushing in the pump 4, (see Figure 6) in which bushing is adapted to move the piston 36. The piston 36 is adapted to seat at one end against the member 37 so as to form an oil tight seat between the end of the member 37 and the piston 36. The piston 36 is hollow, having one end open and carries a spring 38. 39 is a button which bears against one end of the spring 38, and the pressure on the spring 38 can be varied by adjustment of the screw 40 carried in the member 41, secured to the pump 4. 42 indicates a slot in the bushing 35, which slot communicates with the passage 43, which passage 43 communicates with the hole 44 (see Figure 5). When the oil is pumped into the chamber 15, a pressure will be developed in said chamber 15, and will move the piston 36 away from its seat on the member 37, which movement is resisted by the spring 38. The piston will move away from said seat until it uncovers the slot 42, so that part of the oil delivered to chamber 15 will be by-passed into the passage 43, and into the hole 44, and if the pipe plug 45 is removed, the by-passed oil will return to the suction chamber 46 of the pump 4. If it is desirable to return the by-passed oil to the oil tank, then the pipe plug 45 will be screwed into its place, and the plug 46A will be removed and a pipe not shown may be connected in the place of plug 46A, and will run back to the oil tank. It will be obvious to those skilled in the art, that the piston 36 will act both as an oil cut-off valve and a pressure regulating valve, and that the pressure of oil delivered to the pipe 16 will depend on the adjustment of the screw 40.

The oil by-passed from the whirling chamber 24 will return as before described to the valve body 33, through the pipe 32. 47 indicates a diaphragm, which is clamped between the valve body 33 and the valve body head 48, by screws 49. 50 is an adjusting screw carried by the valve body head 48, which contacts with the button 51 mounted in the end of the spring 52, which spring 52 contacts with the member 53, which member 53 bears against the diaphragm 47. The member 54 is screwed into the valve body 33 and acts as a seat for the valve 55. The valve 55 has an enlarged head 56, which contacts with the diaphragm 47, which head 56 engages a spring 57, which spring rests on the member 58, which member is secured to the inner end of the member 54. Oil returning to the inside of the valve body 33 through the pipe 32 will act on the diaphragm 47, and the pressure developed in the chamber within the valve body 33 will cause said diaphragm 47 and valve 55 to move so as to permit oil to flow through the valve and into pipe 34 as before described. Pressure in the chamber within the valve body 33 can be regulated by adjusting the screw 50, and it will be obvious that the adjustment of the screw 50 will regulate the

pressure in the whirling chamber 24 of the nozzle 6. It will be further seen that the valve 55 will not only serve as a pressure regulating valve, but will serve as an oil cut-off valve to prevent oil from flowing by gravity from an oil tank through the oil pump 4 and through the pipes 34 and 32 to the whirling chamber 24 when the burner is not in operation.

33A indicates a hole which communicates with the upper part of the chamber within the valve body 33 and the space around the valve seat of the valve 55. It will be noted that the valve is installed exactly as shown in Figure 4, so that the pipe 34 is on the upper side of the valve. The hole 33A will prevent any air from being trapped within the chamber of the valve body 33. Should any air be trapped in this chamber, there will be an after squirt of oil from the nozzle orifice each time the burner is shut down.

Referring now to Figure 3, 59 indicates packing arranged around the tube 30. The tube 30 has an enlarged portion 60, which serves as a stop for the spring 61 mounted around the tube 30. The member 62 is spaced between the spring 61 and packing 59. The pipe 19 serves as a stop for the enlarged portion 60 of the tube 30 when the oil burner nozzle 6 is not in place, however, when the nozzle 6 is in place, the member 28 will engage the end of the tube 30 and will effect an oil seal between the member 28 and tube 30, and will press the tube backward, as shown in Figure 3, and compress the spring 61, so as to exert pressure on the packing 59 and effect a seal between the oil going to the nozzle 6 and oil being by-passed through the tube 30.

The nipple 63 is attached to the end of the pipe 19 and is threaded to receive the threaded portion of the nozzle 6 as clearly shown in Figure 2.

40 The oil screen 20 is secured to a head 64, which head is arranged to fit nicely over the member 28. The other end of the screen 20 is secured to a head 65, which head is arranged to screw into the inner threaded portion of the nozzle 6. It will be seen that any oil delivered from the pump 4 through the tube 19 will have to pass through the screen 20 before going to the nozzle whirling chamber 24.

66 (see Figure 1) indicates a conventional air whirler mounted around the fuel tube 19, which whirler also acts to center the fuel tube in the air blast tube 5. 67 indicates the conventional electric spark igniter commonly used on oil burners, which igniter receives electric current from the secondary side of a high voltage transformer (not shown) through wires 68.

I have found that in the operation of my oil burner, as illustrated in the accompanying drawings, that if I use a conventional nozzle orifice as shown by the dotted lines in Figure 2 for burning a small gallonage of oil, I get very poor spray and a poor fire and get constant dripping downward from the lower part of the nozzle. With the construction shown in full lines of my nozzle 6, (see Figure 2) I do not get the dripping before mentioned, and I can get a highly efficient fire down to as low as three tenths of a gallon per hour, which fire can be burned in a very small combustion chamber. From repeated tests that I have run, I have found that performance of this nozzle depends primarily upon the size and shape of the delivery orifice, and that the ratio of the length to diameter of the orifice should be a little greater than one, where the ratio of length to diameter of the orifice of the conven-

tional nozzle used on pressure burners is usually between two and three. I have found further that the conventional bell mouth has a tendency to cause the oil to follow the mouth and dribble off the nozzle shell instead of breaking freely away in a cone. This effect becomes so pronounced at low oil rates that there is practically no spray, with the oil all dribbling off the nozzle shell. I have further found that I can use relatively large nozzle orifices with a very low oil gallonage delivered to the fire. I have also found that the nozzle whirler slots 23 can be several times the area of normal slots used in small pressure nozzles. The greater the area of the nozzle slots 23, the larger can be the diameter of the hole 26 in the member 23A. For example, I have taken the core member represented by the numeral 23A from a conventional seven gallon per hour pressure oil burner nozzle, and burned down to three tenths of a gallon per hour, using a nozzle orifice diameter that would normally be used on conventional nozzles when burning between two and three gallons of oil per hour.

I have been using pressures delivered from the oil pump 4 to the nozzle slots 23 of between 150# and 200#, and pressure on the inside of the pipe 32 down to as low as 10#. I have found that I get a greater oil delivery from the nozzle orifice when I have 100# pressure delivered from the pump to the nozzle slots 23 than I do when I have 200# pressure delivered from the pump to the nozzle slots 23 and when I keep the same relatively low pressure in the pipe 32, in both instances. This is due to the fact that with the higher pressure the oil is caused to whirl at much greater velocity in the whirling chamber 24, and apparently sets up a resistance to the outward flow from the nozzle orifice. The higher the pressure of oil to the nozzle slots 23, the greater will be the whirling in the whirling chamber 24, and the better will be the atomization of the oil from the nozzle orifice.

I have found that it is essential, when the oil burner is stopped, that the cut-off valve in the oil conduit from the pump to the nozzle slots 23 cut off at close to the maximum oil pressure being delivered by the pump, and that this cut-off valve should close before the cut-off valve located in the return by-pass line from the nozzle whirling chamber. If the cut-off valve located in the conduit from the nozzle by-pass whirling chamber should close first, then the maximum delivery of oil from the pump would go out the nozzle orifice, and, for example, if we were normally burning one half gallon per hour with say 200# pressure delivered from the pump to the nozzle slots 23 and the valve in the by-pass line from the whirling chamber of the nozzle should close first, we might get an oil delivery of four or five gallons per hour from the nozzle orifice, which delivery would be hazardous if the heat absorbing medium for the oil fire were designed for one half gallon per hour.

In the development of this burner I have found that the viscosity of the oil used in the burner plays an important part in the results that can be gotten, and in order to maintain a uniform delivery of oil from the nozzle, it is essential that the viscosity of the oil be uniform within practical limits.

As I have before mentioned, the whirler slots in the nozzle can be several times the area of the nozzle orifice, and the area of the by-pass hole can be varied according to the total area of the

whirler slots. I have discovered that the ratio of the by-pass hole area to the total area of the whirler slots can be $2\frac{1}{2}$ to 1, and down to as low as $\frac{3}{4}$ to 1. As an example, I have successfully used a by-pass hole having an area of .00062 sq. inch, with a total whirler slot area of .000324 sq. inch, which is a ratio of the by-pass hole area to the total slot area of about 2 to 1. If with this same slot area I use a by-pass hole having an area of .00126 sq. inch, which is a ratio of by-pass hole area to total slot area of about 4 to 1, I find that with this larger diameter by-pass hole, the oil is taken away in a manner that seems to kill the whirl and spoil the atomization of the oil coming from the nozzle orifice.

I claim:

1. In an oil burner, a pump for pumping oil at relatively high pressure, a spray nozzle, a pipe arranged to conduct oil from the pump to the spray nozzle, a whirling chamber adjacent to the nozzle orifice, an oil by-pass pipe connected to said whirling chamber and arranged to by-pass oil from said whirling chamber to the suction side of the pump, an automatic oil cut-off valve arranged in the oil delivery pipe from the pump, a second automatic oil cut-off valve arranged in the oil by-pass pipe which connects to the nozzle whirling chamber, said valves being so constructed that said first named cut-off valve closes before the second named oil cut-off valve when the oil burner is shut off.

2. In an oil burner, a pump for pumping oil at relatively high pressure, a spray nozzle, a pipe arranged to conduct oil from the pump to the spray nozzle, a whirling chamber adjacent to the nozzle orifice, an oil by-pass pipe connected to said whirling chamber and to the suction side of the pump, a combination oil cut-off and pressure regulating valve arranged in the oil delivery pipe from the pump, a second combination oil cut-off and pressure regulating valve arranged in the oil by-pass pipe, said valve being so constructed that said first named valve closes before the second named valve when the burner is shut off.

3. In an oil burner, a pump for pumping oil at relatively high pressure, a spray nozzle, a pipe arranged to conduct oil from the pump to the spray nozzle, a whirling chamber adjacent to the nozzle orifice, an oil by-pass pipe connected to said whirling chamber and to the suction side of the pump, a combination oil cut-off and pressure regulating valve arranged in the oil delivery pipe from the pump, a second combination oil cut-off and pressure regulating valve arranged in the oil by-pass pipe, said valves being so constructed that said first named valve closes before the second named valve when the burner is shut off, the by-passed oil from both valves being returned to the suction side of the pump.

4. In an oil burner, a pump for pumping oil at relatively high pressure, a spray nozzle, a pipe arranged to conduct oil from the pump to the spray nozzle, a whirling chamber adjacent to the nozzle orifice, an oil by-pass pipe connected to the whirling chamber and to the suction side of the pump, an automatic oil cut-off valve arranged in the oil delivery pipe from the pump, a second automatic oil cut-off valve arranged in the oil by-pass pipe, said second valve having a vent therein to prevent any trapping of air within the valve, said first named valve being constructed to close before the second named valve when the oil burner is shut off.

LEWIS L. SCOTT.
